(57) **CLAIM**

The ornamental design for a hat with adjustable wrap, as shown and described.

DESCRIPTION

FIG. 1 is a top perspective view of a hat with adjustable wrap showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof;

FIG. 7 is a bottom elevation view thereof;

FIG. 8 is a top perspective view thereof, shown in use; and,

FIG. 9 is a top perspective view thereof, shown in use.

The broken lines shown in the drawings illustrate portions of the hat with adjustable wrap that form no part of the claimed design.

The broken line outline of the partial human figure in FIGS. 8 and 9 assists in illustrating how the hat with adjustable wrap may appear when worn, but forms no part of the claimed design.
